CAP FOR COLLAPSIBLE TUBES

Phineas A. Brock, Windsor, N. C.

Application September 6, 1946, Serial No. 695,254

1 Claim. (Cl. 220—35)

1

This invention relates to non-removable caps for tooth paste and shaving cream tubes.

It is an object of the present invention to provide a cap for tooth paste and shaving cream tubes which need not be removed to extract the paste or cream therefrom.

It is another object of the invention to eliminate the possibility of losing tube caps by the same being dropped into the drain in the lavatory or in some inaccessible place within the room where the cap is removed.

It is another object of the invention to provide in a non-removable cap a closure portion which is automatically retained in both its open and closed positions and which will be snapped from one position to the other.

According to the invention, the original cap on the tube is removed and discarded and the present cap structure which may be obtained at the drug store as a separate item is secured in place on the threaded outlet from where the original cap was removed. The contents of the tube are thereafter squeezed through the new structure. To make the engagement of the structure, there is provided internal threads which are threaded over the external thread on the tube outlet structure. Extending laterally from one side of the threaded portion are lugs laterally spaced from one another between which are extended lug portions extending downwardly from a laterally extending portion of a closure element adapted to cooperate with the top of the main portion of the structure to close its opening. The lug portions of both the main part of the cap and of the closure element are hinged together by a through pivot pin so that the closure element can be pivoted between open and closed positions. An upwardly extending handle is provided at the end of the lateral extension on the closure element by which a thumb can engage to open or close the closure element. The closure element or cap with its projections are so formed that it can be made from blank stock by a stamping operation. Between the two lugs of the main part of the structure and to the vertically extending wall thereof there is connected for downward expansion a leaf spring. This spring engages one portion of the projection extending downwardly from the closure element and serves as a spring catch to hold the closure element in its closed position and while cooperating with another portion of the closure element projection will hold the closure element in the raised position.

For other objects and for a better understanding of the invention, reference may be had to the

2

following detailed description taken in connection with the accompanying drawing, in which

Figure 1 is the top plan view of the present replaceable closure structure embodying the features of the present invention,

Figure 2 is an elevational view of the closure structure with the closure element in its closed position,

Figure 3 is a cross-sectional view, in elevation, taken along the line 3—3 of Figure 1 and looking in the direction of the arrows thereof, and showing the snap spring catch for retaining the closure element in the closed position on the main part of the structure.

15 Figure 4 is a side elevation, partly broken away and partly in section, of the cap for collapsible tubes, constructed according to an embodiment of this invention, showing the closure element in its raised position.

20 Referring now to the figures, 10 represents the cap structure in its entirety. This structure 10 comprises a main part 11 having internal threads 12 by which the structure is connected to a threaded spout or opening end 13 of a collapsible tube 14.

25 As the original cap is removed from the tube 14 it is replaced by the structure 10. The structure further comprises a pivoted closure element or part 15 adapted to be opened from its normally closed position shown in Figures 2 and 3 to an open position shown in Figure 4. In both of these positions, the closure element will be automatically locked against a movement to one position or the other. The manner in which this is effected will be presently described.

30 35 The main part 11 which is screwed upon the threaded open end of the tube has two laterally spaced lugs 16 and 17 at one side thereof. On the outer wall of the part 11 and between the lugs 16 and 17, there is suspended from near the top edge thereof by a pin 18 a bent up, outwardly-extending, V-shaped snap leaf spring 19 adapted to be compressed by engagement with a corner portion 21 thereof. As the spring 19 is compressed its free lower end will slide downwardly upon the side wall of the part 11.

40 45 The closure element 15 has a laterally extending portion 22 with bent down side lugs 24, one at each side of the extension which are pivoted on a pin 25 extending between the lugs 16 and 17 of the main part. The length of the inner side edge (Figure 3) of each of the lugs 24 is greater than that of the outer side edge, whereby the straight lower edge merges with the forward edge at an acute angle to provide a toe 27 and joins the rear edge with an obtuse angle to pro-

vide a heel 29. This arrangement locates the toe 27 further from the pivot 25 than is the heel 29. The length and shape of these projections 24 is such that the lower inner side edge portions thereof below pivot 25 will be engaged by the corner portion 21 of the spring 19 whereby to urge the lugs and the closure element 15 in a clockwise direction and retain the same over the tube opening.

In order to raise the closure element 15 the toe portion 27 must be moved past the corner portion 21 of the spring 19. While this is done the spring 19 will be temporarily compressed. However, as soon as the toe 27 has cleared the spring point or apex 21, the latter bears on the inclined bottom edge of each lug whereby expansion of the spring tends to snap open the closure. As the closure approaches the Figure 4 position, the spring is again compressed, but to a lesser degree than at first, so that but slight additional pressure is required to urge heel 29 past the point 21 of the spring. Thereafter, expansive pressure of the spring on the outer side edge of the lug 24 tends to positively urge the closure toward the open position. On the extension 22 is a projection 28 which extends upwardly for engagement by the thumb of the user of the tube. The thumb is placed on the projection 28 and pressed downwardly while the tube is held in the same hand to free the projections 24 of the spring 19.

After the closure element has been raised to the full open position as aforesaid, the thumb can be removed from the projection 28 and applied to the tube to collapse the same and cause the extrusion of its contents. To return closure element 13 to its closing position heel portion 29 of each of the lugs 24 must be snapped by the spring as also must each pointed portion 27 of the lugs. A depending flange 31 is formed on the closure element 15 and will surround the top of the part 11 when the closure element is in its

down position. A gasket 26 is seated on the under side of the top of the closure element inwardly of the flange 31 to insure a good sealing connection with the top of the neck 11.

5 While the structure has been described as an accessory for a collapsible tube, it will be apparent that it may form the part of the tube as purchased.

Having described the invention, what is claimed is:

10 In a closure cap having a pair of outwardly-extending, transversely-spaced-apart lugs on one side thereof and a closure element including a depending lug pivoted between said spaced-apart lugs, a V-shaped flat spring fixed at one end on said cap between said spaced-apart lugs and extending outwardly therebetween, the free end of said spring being slidable on said cap upon compression of said spring, and a downwardly and inwardly-inclined edge on said depending lug defining spaced-heel and toe portions engageable with the apex of said spring for biasing said closure element to the open and closed pivoted positions.
